UNITED STATES PATENT OFFICE.

JAMES PLATT, OF UTICA, NEW YORK.

IMPROVEMENT IN BEARINGS FOR VERTICAL SHAFTING.

Specification forming part of Letters Patent No. 39,630, dated September 8, 1863; antedated October 25, 1862.

To all whom it may concern:

Be it known that I, JAMES PLATT, of Utica, in the county of Oneida and State of New York, have invented a new and Improved Anti-Friction Step or Bearing for Vertical Shafting; and I do hereby declare that the following is a full, clear, and exact description of the same, reference being had to the accompanying drawings, making a part of this specification, in which—

Figure 1 is a vertical central section of my invention, taken in the line $x x$, Fig. 2; Fig. 2, a horizontal section of the same, taken in the line $y y$, Fig. 1.

Similar letters of reference indicate corresponding parts in the two figures.

This invention consists in the employment or use of a series of conical rollers placed in an annular frame, which is fitted loosely in an adjustable box placed in or on the framing designed to support the shaft, in combination with a collar placed on the shaft, and provided with a beveled under surface, which rests or bears on the conical rollers, all being arranged in such a manner as to properly support the shaft and admit of its being rotated with but a comparatively small amount of friction.

To enable those skilled in the art to fully understand and construct my invention, I will proceed to describe it.

A represents a portion of a framing, which is designed to support a vertical shaft, B, and C is a box, which is placed on A and fitted on vertical guide-pins a attached thereto, said pins preventing any lateral movement of the box C, but admitting of the latter moving freely up and down on them. The box C is of annular form, or it may be described as being of circular form and provided with an annular groove, b , having an inclined bottom, c , the inner edge of which is higher than the outer edge, as shown in Fig. 1. The box C is provided at the lower part of its outer side with horizontal ears d , through which vertical set-screws D pass and bear upon A.

E is an annular frame, formed of two concentric rings or bands, $e e$, connected at their lower parts by radial bars f , which are at equal distances apart, and between the two rings

or bands $e e$ there are placed conical rollers F, said rollers being between the bars f and fitted loosely on radial fixed shafts g , the ends of which are secured in the rings or bands $e e$. The rollers F may be of cast-steel, chilled cast-iron, or other suitable metal or material, and they rest or bear on the inclined bottom c of the groove b , the frame E also fitting in said groove, and being allowed to turn freely within it, the inclination of the bottom c of groove b corresponding to the inclination of the peripheries of the rollers F, as shown in Fig. 1.

G is a collar, which is placed on the shaft B, and secured thereto by a set screw, H. This collar has a beveled or inclined under surface, h , which rests on the rollers F and sustains the shaft, as will be fully understood by referring to Fig. 1. By this arrangement it will be seen that the shaft B may rotate with but little friction, as the rollers F are not only allowed to rotate independently, but the frame E may also rotate in the groove b , and the latter is supplied with a requisite quantity of oil, which keeps the bearing-surfaces well lubricated at all times.

The shaft B may be adjusted higher or lower by turning the set-screws D.

The independent movement of the frame E is an essential feature of the invention, as it admits of two movements of the rollers F, one on their own axes, and a traveling movement around on the bottom c of the groove b .

I do not claim, broadly, the employment or use of friction-rollers, irrespective of the arrangement and particular manner of applying them, as herein set forth; but,

Having thus described my invention, what I do claim as new, and desire to secure by Letters Patent, is—

The friction-rollers F, fitted in an annular revolving frame, E, in combination with the adjustable box C, placed on the framing A, and the collar G, placed on the shaft B, all arranged as and for the purpose herein set forth.

JAMES PLATT.
